FLUID-OPERATED ALARM

John Gustaf Mauritz Brodén, Malmö, Sweden, assignor to Kockums Mekaniska Verkstads Aktiebolag, Malmö, Sweden, a corporation of Sweden

Application December 19, 1939, Serial No. 310,042
In Sweden December 30, 1938

6 Claims. (Cl. 116—24)

This invention relates to an apparatus for making periodical signals by means of preferably monotonic elastic fluid-operated alarms, such as sirens, in which the supply of air or gas to the alarm is controlled by a shut-off device, such as a valve, actuated by one or more movable members which upon displacement are adapted directly or indirectly to actuate the said shut-off device by different portions so as alternately to open and close the shut-off device.

In previously known control devices of the type indicated for opening and closing the shut-off device, the movable member or members are very complicated due to the fact that they are constructed as rotary members which require special means for imparting rotational movement thereto. Besides, in case of such rotational members it is very difficult to provide means for making different periodical signals.

The objects of my improvement are to provide a simplified member for opening and closing the shut-off device; to utilize a movement required in connection with the operation of the alarm for the actuation of the said member; to provide a control member which will be easily adjustable, whereby to actuate the shut-off device in different ways so as to give different periodical signals; and to provide a control member which can be adjusted by any person to any of the existing signals and which, after it has been adjusted, ensures that the proper signal will be made when the apparatus is operated.

With the above and other objects in view the present invention consists in the construction and novel combination and arrangement of parts hereinafter fully described, illustrated in the accompanying drawing and pointed out in the claims hereunto appended.

The invention is illustrated by way of example in the accompanying drawing, in which:

Fig. 1 is a vertical section of an air pump connected to an alarm apparatus partly shown in the drawing, the upper portion of the pump containing the control member and shut-off device, the figure being shortened in height by omitting cylindrical portions at three places;

Fig. 2 is a horizontal section of a part of the apparatus on line 2—2, Fig. 1;

Fig. 3 is a horizontal section of a part of the apparatus on line 3—3, Fig. 1;

Fig. 4 is a longitudinal section of a part of the piston rod shown in Fig. 1; and

Fig. 5 is a horizontal section of the piston rod shown in Fig. 1.

All of the Figs. 2 to 5 are details of the novel control member according to the invention.

Referring to the drawing, the air pump comprises an upper plate 6, a lower plate 8, an outer cylindrical jacket 14 of sheet metal or the like material, and a similar inner jacket 16, said jackets being inserted between the plates 6 and 8 by means of bolts 10 and nuts 12. The jacket 16 constitutes the cylinder of the air pump. The surfaces of the jackets and plates facing each other should be well ground so as to secure an effective seal. The plates 6 and 8 are provided with abutments 18, 20, 22 for maintaining the jackets in place. A piston 24 provided with a piston rod 26 is arranged to reciprocate in the cylinder 16. The piston has a cover 28 secured thereto by means of screws 30. Piston rings 32, 34 are arranged between the piston and the jacket 16. The piston forms a hollow space 36, and also 10 the piston rod is hollow, the hollow space 38 extending throughout the whole length of the piston rod. The upper wall of the piston has an opening 40, and the cover 28 has an opening 42, said openings being provided with flap valves 44 and 50, respectively, pivoted at 46 and 48, respectively. The pivots are mounted in lugs 52 and 54, respectively, formed on the piston. Normally, the valves are held in closed position by means of leaf springs 56, 58 which are secured to the 20 piston by means of screws 60 and 62, respectively. At the bottom and top of the cylinder 16 there are provided valves, the bottom valve consisting of a rubber or leather packing 64 which is inserted between two plates 66 and 68 which are 25 secured to the packing by means of three screws two of which, 70 and 72, being shown in the drawing. The said screws are threaded into supports 74, 76 projecting from the bottom plate 8, whereby a hollow space 78 is formed between the bottom valve and the plate 8. At the periphery, the packing 64 is bent downwards so that it tightly fits the jacket 16 which has openings 80 for communication between the hollow space 78 and the 30 space between the jackets 14 and 16. 35 In a similar manner, the top valve consists of a rubber or leather packing 82 inserted between two plates 84 and 86, which are secured to the packing by means of three screws 88 one of which only is shown in the drawing. The said screws 40 are threaded into supports 90 pendent from the upper plate 6, whereby a hollow space 92 is formed between the top valve and the upper plate 6. At the periphery, the packing 82 is bent upward so that it tightly fits the jacket 16. At the place 45 where the piston rod 26 extends through the top 50 55

valve, the packing 82 is bent downwards so as to form a tight fit against the piston rod. The upper plate 6 has an opening 94 which connects the space 92 and the space between the jackets 14 and 16 with a chamber 96 located above the plate 6.

The chamber 96 serves as an accumulator for compressed air and is enclosed by an outer jacket 98 and an inner jacket 100, said jackets being inserted between a casing 102 and the upper plate 6 by means of sleeve-like nuts 104 and 106. To this end, the jacket 100 is internally threaded at both ends. The edges of the jackets 98 and 100 and the abutting surfaces of the casing 102 and the plate 6 are plane ground to obtain an effective seal. Annular projections 108, 110, 112, and 114 are provided on the casing 102 and on the plate 6, and it will be seen that the chamber 96 is entirely closed. A packing ring 105 is inserted between the plate 84 and the nut 104. The piston 26 extends through the sleeve-like nuts 104 and 106 which form guides and bearings for the rod with a tight fit so that leakage of air from the space 92 and between the piston rod and the nuts will be entirely or practically entirely prevented.

The chamber 96 is connected through a passage 116 provided in the casing 102 with the siren 118 the mouth 120 of which is partly shown in section in Fig. 1 and the air inlet connection 122 of which is connected to the outlet connection 124 of the passage 116. This passage opens to the chamber 96 by a valve seat 126 adapted to be closed by a shut-off valve 128. By means of a nut 130, the valve is secured to a stem 132 which is longitudinally movable in a bushing 134 mounted in the wall of the passage 116. A spring 127 secured to the casing 102 by means of screws 129 normally keeps the valve in contact with the valve seat.

The casing 102 forms a chamber 138 which at the upper side is closed by a cover 140 attached to the casing by means of circumferentially arranged screws 142, one of which only being shown in the drawing. The piston rod 26 also extends through the cover 140 and is guided therein by a bushing 144 which is rotatably mounted in the cover and has threaded thereon a pointer 146. The pointer is provided on its lower side with a projection 148 which by rotation of the pointer can be brought into engagement with any of a plurality of recesses 150 provided in the cover, only one of these recesses being shown in the drawing. The piston rod is provided with a longitudinal key 145 secured thereto by screws 147, and the bushing 144 has a corresponding keyway (see Fig. 5).

The upper portion of the piston rod has an opening 152 which is disposed so that it will always be located above the cover 140, even if the piston is in its lowermost position. As a result thereof, the space 36 of the piston will always be in open communication with the atmosphere through the opening 152 and the interior 38 of the piston rod. The uppermost portion of the piston rod is provided with a wooden handle 154 secured thereto by means of a pin 156 and a cotter 158 and reinforced by a bushing 160.

The piston rod which can be reciprocated and turned about its longitudinal axis has, in accordance with the invention, a plurality of longitudinally extending outer cam surfaces 162, 164, 166, 168, as shown in Figs. 4 and 5 rather than in the sectional view of Fig. 1. These cam surfaces are shaped in different manners and are

disposed on that portion of the piston rod which always is located above the upper plate 6. Secured to the casing 102 by means of a bolt 172 and a nut 174 is a support 170 the upper portion 5 of which is bifurcated and has mounted therein a pivot 176 fixed by means of a cotter 178. Mounted on the pivot 176 is a lever having two arms 180 located on opposite sides of the piston rod. On the right hand ends, as viewed in the 10 drawing, the arms 180 are arranged to clamp the upper end of the valve stem 132 by means of bolts 182, 184. At a place below the pivot 176, links 186 and 188 are pivoted to the arms 180 as by pivots 190 and 192, respectively (see Fig. 15 3). A roller 194 is rotatably mounted on the links, said roller abutting against one of the cam surfaces of the piston rod. By means of abutments 196 and 198 fixed to the arms 180, the links 186 and 188 are normally held in horizontal 20 position.

The mode of operation of the apparatus described is as follows:

If the piston by pressure on the handle 154 is moved downwards from its uppermost position, the air present in the cylinder 16 below the piston will be compressed, since the valve 50 is 25 kept in closed position by the spring 58. At the same time, the valve 48 will be opened, since sub-atmospheric pressure will prevail above the piston, and air will flow through the opening 152, the interior 38 of the piston rod, and the opening 40 into the space above the piston. When the pressure in the space below the piston has 30 been increased to a certain value the peripheral 35 bent-down portion of the packing 64 will be pressed inwardly so that the compressed air will flow to the space 78 and hence through the space between the jackets 14 and 16 and through the opening 94 into the chamber 96. During the 40 downward movement of the piston rod the roller 194 will be actuated by the cam surface 162 so as to impart to the lever 180 a rocking movement about the pivot 176, with the result that the shut-off valve 128 will be alternately opened and closed 45 so as to permit of periodical flow of air through the passage 116 and to the siren which will make signals of a character corresponding to the shape of the cam surface 162.

When the handle 154 is pulled upwards, the 50 valve 48 will be closed, and the air in the space above the piston will be compressed. When the air has been compressed to a certain value, it will 55 flow past the peripheral portion of the packing 82 into the space 92 and hence through the opening 94 into the chamber 96. Since the roller 194 is mounted on the links 186, 188, it will be turned, during the upward stroke of the piston, about the pivots 190, 192 in an anti-clockwise direction 60 out of the path of movement of the cam surface 162 without actuating the lever 180, with the result that the shut-off valve 128 will be kept in closed position during the upward stroke. During the 65 downward stroke, the links 186, 188 rest on the abutments 196, 198, and in this case, the roller 194 can be regarded as being rigidly mounted in the arms 180. While I have found that the provision of the links 186, 188 is very advantageous, it will be evident that the roller may be mounted directly in the arms 180.

70 The pointer 146 is slightly resilient so that the projection 148 thereof can be brought into engagement with any of the recesses 150 the number and location of which corresponds to the number and location of the cam surfaces 162, 164, 166, 168. Suitable marks on the cover 140

may be provided to indicate which of the different signals corresponds to the position of the pointer. Since the bushing 144 is keyed on the piston rod, it will be seen that the pointer will follow any turning movement of the piston rod, and after the pointer has thus been adjusted to a certain signal, the angular position of the parts will be maintained, during the reciprocation of the piston, due to the key connection and the cooperation of the projection 148 with the corresponding recess 150.

It will be evident from the above description that the invention provides a simple control member for effecting the opening and closing movements of the shut-off valve, in contrast to rotary control members which require additional means for imparting rotary movement to the control member. A further advantage of the novel construction resides in the fact that the movement of the piston rod is directly utilized for actuating the air admission valve. A still further advantage consists in the possibility of providing a plurality of different cam surfaces on a single piston rod, which surfaces can be put into operative position in a simple manner by turning the piston rod about its longitudinal axis and thereby electing any desired signal. These signals can be easily adjusted by means of the pointer, and the elected position of the parts will be maintained by the cooperation of the parts as described.

While in the foregoing description I have confined my consideration to a preferred embodiment of my invention, it will be understood that the invention is not confined to this specific arrangement but may be modified as to constructional details within the scope of the appended claims construed as broadly as is consistent with the prior art.

What I claim is:

1. In a fluid-operated alarm, an alarm device, valve means for controlling the flow of fluid to said alarm device, means for compressing the fluid, a member having a longitudinal cam surface and being arranged to be reciprocated, said means for compressing the fluid being connected with said member to reciprocate the same, and means arranged to be actuated by cooperation with said cam surface for alternately opening and closing said valve means in response to movements of said member so as to effect periodical flow of fluid to the alarm device for producing signals of character corresponding to the shape of the cam surface.

2. In a fluid-operated alarm, an alarm device, valve means for controlling the flow of fluid to said alarm device, a member having a plurality of different longitudinal cam surfaces around its circumference, means for imparting a reciprocating movement to said member, valve actuating means arranged to be actuated by cooperation with any of said cam surfaces for alternately opening and closing said valve means in response to movements of said member so as to effect periodical flow of fluid to the alarm device for pro-

ducing signals of character corresponding to the shape of the cam surface in operation, and means for turning said member, whereby to bring said valve actuating means into contact with any of said cam surfaces.

3. In a fluid-operated alarm, an alarm device, a reciprocating fluid pump including a piston and a piston rod, a conduit for supplying fluid compressed in said pump to said alarm device, a valve in said conduit for controlling the flow of compressed fluid to said alarm device, said piston rod having a longitudinal cam surface, and valve actuating means arranged to be actuated by cooperation with said cam surface for alternately opening and closing said valve in response to movements of said piston rod.

4. In a fluid-operated alarm, an alarm device, valve means for controlling the flow of fluid to said alarm device, means for compressing the fluid, a member having a plurality of different longitudinal cam surfaces, said means for compressing the fluid being connected with said member in order to reciprocate the same, valve actuating means arranged to be actuated by cooperation with any of said cam surfaces for alternately opening and closing said valve means during one stroke of said member, means for releasing said valve actuating means during the return stroke of said member, and means for turning said member, where to bring said valve actuating means into contact with any of said different cam surfaces.

5. In a fluid-operated alarm, an alarm device, valve means for controlling the flow of fluid to said alarm device, means for compressing the fluid, a member having a plurality of different longitudinal cam surfaces, said means for compressing the fluid being connected with said member in order to reciprocate the same, valve actuating means arranged to be actuated by cooperation with any of said cam surfaces for alternately opening and closing said valve means in response to movements of said member so as to effect periodical flow of fluid to the alarm device for

producing signals of character corresponding to the shape of the cam surface in operation, means for turning said member whereby to bring said valve actuating means into contact with any of said cam surfaces, and means associated with said member for indicating that of said cam surfaces which is in contact with said valve actuating means.

6. In a fluid-operated alarm, an alarm device, a reciprocating fluid pump including a piston and a piston rod, a conduit for supplying fluid compressed in said pump to said alarm device, a valve in said conduit for controlling the flow of compressed fluid to said alarm device, said piston rod having a longitudinal cam surface, means arranged to be actuated by cooperation with said cam surface for alternately opening and closing said valve during one stroke of said piston, and means for releasing said valve actuating means during the return stroke of said piston.

JOHN GUSTAF MAURITZ BRODÉN.
